[57] CLAIM

The ornamental design for a practice tethered golf ball, as shown and described.

DESCRIPTION

FIG. 1 is a perspective view of the practice tethered golf ball embodying the design;

FIG. 2 is a front elevational view thereof;

FIG. 3 is a rear elevational view thereof;

FIG. 4 is a side elevational view thereof;

FIG. 5 is a side elevational view thereof;

FIG. 6 is a top plan view thereof; and,

FIG. 7 is a bottom view thereof.

The tether is shown interrupted to indicate indeterminate length.

FIG. 1

FIG. 2

FIG. 3

FIG. 4

FIG. 5
